Primary Examiner — David Muller*Assistant Examiner* — Nathan Johnston(74) *Attorney, Agent, or Firm* — Alford Law Group, Inc.;
William E. Alford(57) **CLAIM**

The ornamental design for a biological fluid collection device, substantially as shown.

DESCRIPTION

FIG. 1 is a top front right perspective view for a biological fluid collection device showing our new design;

FIG. 2 is a top rear left perspective view thereof;

FIG. 3 is a bottom rear left perspective view thereof;

FIG. 4 is a bottom front right perspective view thereof;

FIG. 5 is a right side elevation view thereof;

FIG. 6 is a left side elevation view thereof;

FIG. 7 is a front side elevation view thereof;

FIG. 8 is a rear side elevation view thereof;

FIG. 9 is a top plan view thereof; and,

FIG. 10 is a bottom plan view thereof.

All broken lines represent unclaimed environmental matter.
The broken lines form no part of the claim.**1 Claim, 5 Drawing Sheets**| (56)	References Cited
